LUMBUS, OHIO, A CORPORATION OF OHIO.

SAND-REEL STRUCTURE.

Application filed May 21, 1927. Serial No. 193,332.

Our invention relates to sand reel structure. It has to do primarily with chain driven sand reels and particularly with the means for effecting driving and braking of the sand reel shaft. It also aims to meet certain conditions already existing in sand reel structures generally in use at the present time.

At the present time, it is common practice 10 in drilling and bailing of oil, gas or artesian wells to use either friction driven sand reels with a back brake equipment or chain driven sand reels, the latter being more or less a recent development.

15 Our invention aims to provide a novel and superior type of chain driven sand reel. It further aims to provide a unitary driving and braking mechanism which may either be installed as a part of a sand reel or which 20 may be installed upon a sand reel shaft which is already in use. In connection with the installation of our unitary driving and braking mechanism upon a sand reel shaft which is already in use, one of the 25 objects of our invention is to provide a structure which is of the proper dimensions to accommodate the already existing space upon the majority of sand reel structures in use and, at the same time, to form an efficient 30 operating mechanism.

One feature of our invention consists in the provision of a drum with a brake band operating on the outside for stopping the rotation thereof at any desired point and with 35 a clutch band operating on the inside for effecting rotation of the drum whenever desired. The structure is such as to provide a maximum of simplicity and efficiency.

Another feature of our invention consists 40 in the provision of a single means for moving either the clutch into driving relation to the drum or for rendering the brake band structure effective to check rotation of the sand reel. This single means comprises a 45 plurality of levers and operating links which are of such form and so arranged as to reduce the number of levers necessary to a minimum and, at the same time, to insure that either the clutch or the brake band structure may be moved to driving position or that both may be moved to neutral position 50 with a minimum of effort.

Another feature of our invention resides in the fact that we have provided a driving sprocket which is so mounted upon the band wheel shaft and has such parts associated therewith as to insure proper alignment of the driving and driven sprockets of the sand reel structure without exceeding the space already existing in the majority of units in 60 the field at the present time.

In order to obtain this proper alignment and, at the same time, to provide a structure capable of fitting units already installed, we have devised a novel structure. One of the 65 features of this novel structure consists in the provision of a collar or sleeve upon the band wheel shaft which bears firmly against the driving sprocket carried by the shaft and prevents longitudinal movement of the shaft 70 as well as bracing the sprocket against waddling. This sleeve is preferably secured against movement on the band wheel shaft and it slidably supports a movable jaw clutch member which cooperates with clutch 75 teeth upon the sprocket. This provides a compact and efficient structure which makes possible the proper alignment of the driving and driven sprockets of the sand reel structure and which does not exceed the 80 space limits indicated.

The preferred embodiment of our invention is shown in the accompanying drawings wherein similar characters of reference designate corresponding parts and wherein 85

Figure 1 is a perspective view of our sand reel unit without the driving sprocket mechanism.

Figure 2 is a perspective view of the driving and braking unit which we preferably 90 utilize in our invention.

Figure 3 is a perspective view of our clutch band unit which is insertible into and removable from our drum as a unit.

Figure 4 is a detail view of one of the cams 95 utilized by us.

Figure 5 is a sectional view taken on line 5-5 of Figure 6 of a means for supporting and adjusting each of our cams.

Figure 6 is a side elevation of a means for 100 regulating the amount of adjustment and for indicating when the clutch bands are worn to an extent requiring removal.

Figure 12 is a longitudinal section showing our clutch drum and means whereby the bore of the hub may be varied to accommodate various sand reel shafts.

20 Figure 13 is a perspective view of a modification of our clutching and braking unit, wherein the clutch parts are also used as braking parts.

25 Figure 14 is a perspective view of a modified form of clutch-operating mechanism which we may utilize.

In the drawings, our sand reel structure is shown mounted upon skids 1. It comprises bearings 2 and 3 and a shaft 4. It 30 also comprises the reel 5 and a driving and braking unit.

The driving and braking unit, in its entirety, is best illustrated in Figures 1 and 2. It comprises a hollow drum 6 with spaced 35 outer peripheral flanges 7. These peripheral flanges form a channel for a brake band 8 having the usual lining 9 of asbestos or other material.

40 One end of the brake band 8, as shown in Figure 1, is provided with a connecting element 10 that is in turn connected to one of the skids 1 by means of bolts 11. The other end of the brake band (as shown in Figures 1 and 2) is also provided with a connecting element 12 that is secured to the free end of a lever 13 which is fulcrumed at 14 and is designed to be operated to apply or release the brake band by a reach rod 15. This lever 13 is also connected to a removable clutch 45 element in a manner that will be described hereafter.

The drum 6 carries an integral web 16 and an integral hub 17 which is concentric with the outer periphery of the drum and 50 which extends inwardly as a cylindrical member. This cylindrical member is designed to receive, upon its periphery, a clutch frame which is illustrated in Figure 3 and which will subsequently be described in detail.

55 The hub 17 may be bored to accommodate standard size sand reel shafts. This hub is keyed to the shaft 4 as at 21' and is held in position on the shaft 4 by the set screws 16'.

Our clutch frame is shown best in Figure 3. It comprises a flange 18 and a central hub member 19 which is designed to fit upon the hub member 17 in the manner shown in Figure 2. It further comprises 70 radially extending arms 20 which are bifurcated as at 21. These bifurcations 21 are designed to support fixed ends of the clutch bands 22 pivotally mounted as at 23. The clutch bands carried by this bifurcated arm 20 are designated by the numeral 24 and are substantially semi-circular in form. Two clutch bands are shown but good results may be obtained by using only one of such bands. 75

The opposite ends of these clutch bands are 80 relatively free, being normally drawn inwardly by coil springs 25 which connect to the shoes 26 of the clutch bands and which also connect to the radially extending elements 20 of the hub.

85 It will be readily understood that these clutch bands are rendered effective by expanding them against the internal periphery of the drum 6. We have accomplished this by a novel mechanism, embodying cams 90 which serve to force the relatively free ends of the clutch bands outwardly against the tension of springs 25. This operating mechanism is illustrated in detail in Figures 2, 3 and 4.

95 The shoes 26 upon the relatively free ends of the clutch bands are provided with lugs 27, as shown in Figures 3 and 4, and these lugs are designed to be contacted and moved to force these free ends outwardly by cams 100 28 rigidly carried upon shafts 29. These shafts 29 are provided with crank arms 30 which are connected to and operable by links 31. These links 31 are in turn operated by bell-crank levers 32 fulcrumed at 33 upon the members 20 and having their opposite ends pivotally connected to operating rods 34. As shown in Figures 2 and 3, the operating rods extend through the flange 105 18 of the clutch frame, through the driven sprocket structure mounted upon the hub 19, and are connected at their reduced outer ends to a plate 35 formed in sections and being a part of a movable collar construction or clutch element 36. 110

115 The movable clutch element 36 is preferably formed in semi-circular sections 39 designed to be bolted together by bolts 37 extending through lugs 38 upon such sections. These sections of the clutch element 36 are integral with a collar 40 which is likewise in sections and which is channeled at 41 for the reception of the block 42 of a yoke lever 43.

120 The yoke lever 43 is fulcrumed as at 44 and has its lower end pivoted as at 45 (see Figure 1) to one end of a bell-crank lever 46. This bell-crank lever 46 is fulcrumed as at 47 and has its opposite end pivoted as at 48 to a link 49. This link 49 is pivoted at 125 130

its opposite end to the lever 13 which operates the brake band, being connected thereto on the opposite side of the fulcrum 14 and in between this fulcrum and the connecting point of the reach rod 15.

In operation of these cams, the inward movement of the collar 40 of the movable clutch member towards the drum 6 exerts a force upon the rods 34 by means of the plate 35. This force operates through the bell-crank 32 to move the links 31 radially inward, with the result that the crank arms 30 are swung to force the cams 28 against the lugs 27 upon the relatively free ends of the clutch band. This exerts a powerful pressure upon these free ends and serves to force the clutch bands into clutching contact with the inner periphery of the drum 6. Such action results in the establishment of a driving contact between the clutch frame and the drum.

The effectiveness of the cam elements 28 in expanding the clutch bands may be regulated by varying the relation between each cam 28 and its crank arm 30. For instance, in Figure 5, it will be noted that the cam 28 is keyed upon the shaft 29. This shaft 29 extends through the plate 18 of the clutch frame, being supported in this plate by means of a sleeve 57.

The shaft 29 is provided integrally upon its outer end with an adjusting flange 53 having a lug 54 upon its periphery. The sleeve 57 is also provided with an integral flange 58 lying outside of the plate 18 and in abutting relation with the flange 53. This flange 58 is also provided with a lug 54' upon its periphery, this lug being wider than the flange 58 and extending laterally across the periphery of the flange 53.

These flange members 53 and 58 are provided with a series of apertures 59 which are capable of successive alignment. A bolt 60 is provided and this bolt is adapted to extend through aligned apertures in both flanges, being shown in one pair of aligning apertures in Figures 5 and 6.

The crank arm 30 is loosely mounted on the shaft 29 but has its hub laterally extended to form a sleeve 30'. This sleeve 30' is provided with an additional angular extension 55 which fits into a complementary socket 56 of the sleeve 57, so that movement of the crank arm 30 will be transmitted to the sleeve 57 to oscillate the same with the result that, whenever this sleeve 57 is bolted to the shaft 29 through the medium of the abutting flanges 53 and 58 and the bolt 60, the shaft 29 will be oscillated and will consequently oscillate the cam 28. Normal actuation of this cam 28 to expand its clutch band or relieve it from pressure is effected by the swinging of the crank arm 30, as has been described.

When it is desired to adjust the cam, the

bolt 60 is removed from one pair of aligning apertures and the adjusting flange 53 is rotated to bring another pair of apertures into alignment, the sleeve 57, flange 58 and crank arm 30 remaining stationary. This rotation of the flange 53 results in rotation of the shaft 29 and in changing the initial operating position of the cam 28 with relation to the lug 27 of the expanding band and with relation to the crank arm 30. Thus, successive adjustments may be made from time to time to compensate for the wear upon the clutch bands. It will be seen that, with this structure, the cam 28 and the arm 30 form a bell-crank and that by means of the adjusting device the angle between the arms of the bell-crank, namely, the cam 28 and the arm 30, can be increased or decreased.

The purpose of the lugs 54 and 54' is to provide an adjusting limit which will prevent further tightening of the clutch bands after the asbestos or other clutch band lining has become too worn for further effective use. The lugs 54 and 54' are so mounted that they will contact with each other to stop further adjustments when the clutch linings reach a point where they are no longer effective to the desired degree. This feature is of considerable importance in practical operation because it insures against the occurrence of accidents due to the use of clutch bands after they become too worn to be effective and practically does away with the danger of fire caused from sparks from the points where the clutch linings are worn out, allowing metal to rub on metal.

It will be seen from this that we have provided a simple and effective means for compensating for wear of the clutch bands and for insuring removal of these bands when worn out. The means of adjustment contemplate varying the operating path of the cams when necessary or desirable. Obviously, similar results could be obtained by varying the length of such paths. Likewise, it will be understood that this adjusting mechanism may be utilized to obtain the proper leverage action, regardless of the question of wear. Rotation of the flange 53 in a clockwise direction will serve to tighten the clutch and rotation in a counter-clockwise direction will serve to loosen the clutch.

It will be understood that the reach rod 15 when moved to the full extent in one direction serves to actuate the lever 13 to release the brake band 8 and to simultaneously move the movable clutch member into such position that the clutch bands are expanded to produce a driving contact with the inner periphery of the drum, this last being effected by the action of the cams upon the relatively free ends of the clutch band. On the other hand, movement of the reach rod 15 to its full extent in the opposite direction serves to so move the cams as to permit their

contraction by the springs 25 operating upon their relatively free ends and at the same time the lever 13 is effected to move the brake bands into braking contact with the outer periphery of the drum. The controlling mechanism is so constructed that the cam cannot pass the center of the lug 27 and therefore cannot jamb. It will also be understood that the reach rod 15 may be moved to a neutral position, in which no driving contact is established between the clutch bands and the inner periphery of the drum and no braking contact is established between the brake bands and the outer periphery of the drum.

Mounted upon the hub member 19 of the clutch frame is a sprocket unit. This sprocket unit is made up of an integral flange 18' on the hub member 19 and of a semi-circular toothed member 62 formed in sections and held to this integral flange by a sectional plate 63 and bolts 64. It will be obvious that rotation of the toothed member or sprocket 62 will result in rotation of the clutch band frame. It will also be obvious that the sectional toothed member may be readily replaced when worn.

Rotation of this sprocket member 62 is designed to be effected by means of a sprocket chain 65 (see Figure 10). This sprocket chain 65 is adapted to be driven by sprocket 66 which is formed in half sections and mounted upon the band wheel shaft 67. The sprocket is provided with a bushing 68 that is likewise formed in sections and may be given any desired bore so that it can be applied to band wheel shafts of any normal size.

This driving sprocket is idly mounted upon the band wheel shaft and is provided with clutch jaws 69 upon one side thereof for cooperation with a movable jaw clutch member 70. This movable jaw clutch member 70 is channeled for the reception of suitable operating mechanism and it is splined upon a sleeve 71 which is keyed upon the band wheel shaft 67 and held against lateral movement thereon by set screws 71a.

Both the jaw clutch member 70 and the sleeve 71 are formed in sections and therefore are readily removable and replaceable, just as is the sprocket 66. Furthermore, the sleeve 71 prevents wabbling of the sprocket 66 and also prevents longitudinal movement of the band wheel shaft 67. Likewise, the mounting of the jaw clutch member upon the sleeve which prevents longitudinal movement of the band wheel shaft and which prevents wabbling of the sprocket so economizes space on the band wheel shaft that our chain driven sand reel unit may be applied to drilling rig structures already existing without exceeding the space already provided therein and at the same time obtain proper alignment of the driving and driven

sprockets of the sand reel structures. This structure and the manner of mounting of these parts is novel and highly advantageous because it renders possible the adaptation of our chain driven sand reel to those drilling rig structures generally in use in the field today.

In the modification shown in Figure 11, it will be seen that we have utilized a single clutch band 72 which is secured to the clutch band frame at a central point as at 73. The ends are provided with shoes 74 and 75 which are designed to be operated by cams 76 and 77 mounted upon an oscillatable shaft or spindle 78. With this structure, oscillation of the shaft or spindle 78 in a clockwise direction will serve to produce expansion of the brake band to establish a driving contact with the internal periphery of the drum.

In the modification shown in Figure 12, the drum 6 has the web 16 removably connected to a hub member 17' by bolts 20'. This hub member 17' may be varied as to bore as desired to accommodate any sand reel shaft likely to be found in the field. It may be keyed to the shaft and held thereon by a set screw or set screws 16'. Thus, by selecting a hub having a bore of the proper diameter to fit the shaft on which the mechanism is to be disposed, our driving and braking unit may be applied to any sand reel shaft.

In the modification shown in Figure 13, the clutch and operating mechanism therefor is substantially identical with the clutch and operating mechanism shown in Figures 1, 2 and 3. However, the brake band mechanism is dispensed with and a drum 80 is used. This drum may be identical with the drum shown in the other figures or may have its exterior face smooth; in either case no brake band is utilized. Likewise, the reach rod 82 corresponds to the reach rod 15, except that it connects directly to one arm of a bell-crank lever 84. The other end of the bell-crank lever operates a yoke lever 85 for moving the movable clutch member into and out of operative position. Such clutching mechanism may also be used as a brake since it is obvious that a brake would only be desired when the sand reel and associated mechanism is rotating contra-clockwise. By moving the clutch member into engagement, the power and weight of the driving means would tend to rotate the sand reel in the opposite direction, furnishing all the brake necessary under some conditions.

The modification shown in Figure 14 provides for the substitution of an equalizing yoke 35' for the plate 35. This equalizing yoke is pivotally mounted intermediate its ends as at 91 and is pivoted at its outer ends as at 92 and 93 to rods 94 which are the equivalents of the rods 34 of Figure 2. It

will be apparent that this equalizer serves to insure an equal pressure upon the two clutch bands even though one clutch operating cam may be adjusted a little ahead of the other or if, for some reason, one clutch band wears a little more rapidly than the other.

From this description it will be seen that we have provided a chain driven sand reel embodying numerous features of novelty.

10 One of these features arises from the fact that we have provided a single driving and braking unit which may be applied or removed as an entity and may be applied to sand reel shafts of different size. Furthermore, the structure is extremely simple and efficient, this being partly due to the fact that a single drum provides both a braking and a clutch surface.

Another feature of our invention consists 20 in the provision of a clutch band frame which is separable as a unit from the drum. Another feature arises from the fact that the clutch bands are operated by cams with constant lever arms and that these cams 25 exert constant forces, serving to expand the clutch bands against the inner periphery of the drum.

A still further feature arises from the fact that the clutch frame can be easily slid 30 out from the inside of the drum and that this permits relining of the clutch bands without dismantling the entire sand reel.

Another feature arises from the fact that our sand reel may be seated in the same 35 bearing used by a friction drive sand reel, the clutch and brake assembly being introduced to replace the brake and friction drum of a friction drive sand reel to connect into a chain driven sand reel.

40 Another feature of our invention arises from the structure of the driving sprocket and its operating mechanism, together with the manner of mounting this structure. This structure is such that we are able to 45 utilize the space normally taken up by the set collar commonly provided with the rig irons. By this method of construction, we are able to reduce the maximum distance required between the front jack post bearing 50 and the hub of the band wheel flange to 10 inches, as against 15 inches required by other chain driven sand reels at present on the market. This permits the installation of our jaw clutch structure on a standard rig 55 without moving the band wheel or bull wheel.

Another feature of our invention arises from the unusually large lever ratio that we are able to provide by the use of cams for 60 actuating the expanding bands. Thus, we are able to obtain a very large band area while, at the same time, engagement is easily effected by a slight pressure on the operating lever. Furthermore, release of the band may be instantly effected without rub-

bing of loose and noisy members. Likewise, sticking of the clutch is impossible and this, in itself, is very important.

A further feature of our invention resides in the fact that the clutch bands on the inside of the drum have been so arranged that practically all the working parts of the mechanism associated with the friction clutch are enclosed. Such arrangement and construction of parts excludes practically all 70 water, oil, sand and other foreign material from the working parts and, consequently, tends to insure the proper functioning of these parts. The compact nature of the clutch construction, together with the absence of protruding parts, is also an important feature of our invention.

It will be apparent that we have provided a simple, fool-proof method of tightening or loosening the clutch bands and that this 80 adjustment may be made with a minimum amount of time and labor. Furthermore, the adjustment can be accomplished from the outside of the mechanism so that any one who can loosen or tighten a nut can 85 make the adjustment, that is, no expert mechanic is required.

The essential units of our apparatus are 90 readily removable and may be readily transferred from one rig to another. Thus, one 95 reel will serve a number of locations and the transfer can be made with a minimum of difficulty. Likewise, the rigid construction used makes for longevity and efficient operation.

Having thus described our invention, what 100 we claim is:

1. Sand reel structure comprising a sand reel shaft, a drum, a band movable into contact with a periphery of said drum, a cam for effecting such movement, and means for adjusting said cam to vary its effectiveness.

2. Sand reel structure comprising a sand reel shaft, a drum, a band movable into contact with a periphery of said drum, a cam for effecting such movement, and means for varying the operative path of said cam.

3. Sand reel structure comprising a sand reel shaft, a drum, means for clutching said 115 drum, said last means being removable from said drum as a unit.

4. Sand reel structure comprising a sand reel shaft, a drum, clutching mechanism insertible into said drum and operable against the interior thereof, said mechanism being removable as a unit.

5. Sand reel structure comprising a sand reel shaft, a clutch structure, means for adjusting said clutch structure, and means for visually indicating when further adjustment is undesirable.

6. Sand reel structure comprising a sand reel shaft, a driven clutch member, a driving clutch member, a cam for forcing said driv-

- 6
- ing clutch member into operative relation to said driven clutch member, and means for adjusting said cam to vary its effectiveness.
- 5 7. Sand reel structure comprising a sand reel shaft, a driven clutch member, a driving clutch member, a cam for forcing said driving clutch member into operative relation to said driven clutch member, operating mechanism for said cam, and means for changing the initial position of said cam to vary its effectiveness.
- 10 8. Sand reel structure comprising a sand reel shaft, a driven clutch member, a driving clutch member, a cam for forcing said driving clutch member into operative relation to said driven clutch member, operating mechanism for said cam, means for adjusting the path of said cam to compensate for wear.
- 15 9. Sand reel structure comprising a sand reel shaft, a drum, a band movable into contact with a periphery of said drum, a cam for effecting such movement, means for adjusting said cam to vary its effectiveness, and means for preventing such adjustment beyond a predetermined point.
- 20 10. Sand reel structure comprising a sand reel shaft, a drum, a band movable into contact with a periphery of said drum, a cam for effecting such movement, means for varying the operating path of said cam, and means for limiting such variations.
- 25 11. Sand reel structure comprising a sand reel shaft, a drum, clutching mechanism insertible into said drum and operable against the interior thereof, said mechanism embodying an expansible band structure and operating cam therefor, said band structure and operating cam being removable as a unit.
- 30 12. Sand reel structure comprising a sand reel shaft, a drum, clutching mechanism insertible into said drum and operable against the interior thereof, said mechanism comprising cam and operating levers and links and being removable with said cam, levers and links as a unit.
- 35 13. Oil, gas and artesian well structure comprising a shaft, a drum, a band movable into contact with a periphery of said drum, a cam for effecting such movement, leverage mechanism for operating said cam, and means intermediate said cam and said leverage mechanism for adjusting said cam with relation to said leverage mechanism to vary its effectiveness.
- 40 14. Oil, gas and artesian well structure comprising a shaft, a drum, a band movable into contact with a periphery of said drum, a cam for effecting such movement, a rocking shaft upon which said cam is mounted, a sleeve on said rocking shaft, a lever connected to said sleeve, means for connecting said rocking shaft and said sleeve, said means being adjustable to vary the relation between said sleeve and said rocking shaft, and means for operating said lever to render said cam effective.
- 45 15. Oil, gas and artesian well structure comprising a sand reel shaft, a driven clutch member, a driving clutch member and a driving sprocket, said driven clutch member, said driving clutch member and said driving sprocket being laterally movable as a unit.
- 50 16. Oil, gas and artesian well structure comprising a shaft, a driven clutch member, a hub extension on said driven clutch member, a driving clutch member slidable on and off of said hub extension.
- 55 17. Oil, gas and artesian well structure comprising a shaft, a driven clutch member, a hub extension on said driven clutch member, a driving clutch member slidable on and off of said hub extension and means for securing said driving clutch member upon said hub extension.
- 60 18. Oil, gas and artesian well structure comprising a shaft, a driven clutch member, a hub extension on said driven clutch member, a driving clutch member mounted on said hub extension and a driving sprocket carried by said driving clutch member.
- 65 19. Oil, gas and artesian well structure comprising a clutch member, a hub for said clutch member, arm members extending radially from said hub, and brake bands carried by said arm members.
- 70 20. Oil, gas and artesian well structure comprising a clutch member, a hub for said clutch member, arm members extending radially from said hub, brake bands carried by said arm members, and cams carried by said arm members for actuating said brake bands.
- 75 21. Oil, gas and artesian well structure comprising a clutch member, a hub for said clutch member, brake bands carried by said clutch member, operating cams for said brake bands, and arms upon said hub member for carrying said cams.
- 80 22. Oil, gas and artesian well structure comprising a shaft, a driven clutch member, a driving clutch member, said members so constructed that they produce an enclosed space when in operative relation, clutch bands and operating mechanism therefor mounted within such enclosed space and having actuated rods extending through one of said members.
- 85 23. Oil, gas and artesian well structure comprising a driven clutch member, in the form of a drum open at one side, a driving clutch member normally fitting within said drum, said driving clutch member comprising a disk which closes the open end of

said drum, and brake bands and operating mechanism therefor carried within said enclosed drum.

24. Oil, gas and artesian well structure comprising a shaft, a drum, clutch mechanism operating against the interior surface of said drum for driving it, a brake band operating against the exterior surface of said drum for braking it, one end of said band being tied in fixed position, a clutch collar for operating said clutch, a lever for operating said collar, a bell crank lever for operating said last named lever, and an operating lever connected on one side of its fulcrum to one end of said bell crank lever and on the other side of its fulcrum to the free end of said brake band.

25. Oil, gas and artesian well structure comprising a sand reel shaft, a clutch member on said shaft, a detachable hub struc-

ture for said clutch member, a band wheel shaft, a driving sprocket on said band wheel shaft and a detachable hub member for said sprocket, a driven sprocket on said sand reel shaft, and a sprocket chain for transmitting power from said band wheel sprocket to said sand reel sprocket.

26. A clutch for oil, gas and artesian well structure comprising a drum, expanding band structure, a plurality of cams for effecting such expansion, leverage mechanism for operating said cams, and means for equalizing the effective expanding force for said cam.

In testimony whereof we, hereby, affix our signatures.

RICHARD R. BLOSS.
